ATTORNEYS.

UNITED STATES PATENT OFFICE.

WILLIAM A. SMITH, OF WILMINGTON, DELAWARE.

BOOK-CASE.

SPECIFICATION forming part of Letters Patent No. 293,101, dated February 5, 1884.

Application filed August 2, 1883. (No model.)

To all whom it may concern:

Be it known that I, WILLIAM A. SMITH, of Wilmington, in the county of New Castle and State of Delaware, have invented a new and Improved Book-Case, of which the following is a full, clear, and exact description.

The object of my invention is to provide a book-case fitted with devices to lock the books in the case, and thus prevent their abstraction by unauthorized persons.

Reference is to be had to the accompanying drawings, forming part of this specification, in which similar letters of reference indicate corresponding parts in all the figures.

15 Figure 1 is a front view of a book-case made in accordance with my invention, and showing the locking-frame in position to prevent the removal of books from the case. Fig. 2 is a side view of the book-case, partly broken 20 out and in section on line $x-x$, Fig. 1. Fig. 3 is a sectional plan view on line $y-y$, Fig. 2, with a book-shelf partly broken away. Fig. 4 is a sectional elevation on the line $z-z$, Fig. 3; and Fig. 5 is an elevation of one of the slotted plates of the locking-frame, in larger size.

25 I will here show and describe my invention as applied to an open-front book-case; but my improvements may be fitted with facility to book-cases having a front closed by either sliding or folding doors.

The letter A represents the book-case, made with sides a , back b , and any desired number of book-shelves, c —in this instance five shelves being shown—and the case may have 35 the usual base, d , and a top, e , of any desired design.

The letter B represents the locking-frame, which consists, essentially, of vertical bars or moldings f , joined or connected by horizontal 40 cross-bars or moldings g . There are preferably to be as many of the vertical bars f as there are vertical sides and partitions to the book-case, and as many cross-bars as there are shelves between the vertical sides and partitions of the book-case. In the drawings a medium-sized or narrow case is represented. Consequently no vertical partitions are employed between the sides a . The cross-bars g are 45 spaced apart the same distance as the shelves c , so that the frame B may be raised or low-

ered to bring the bars g in line with or over the front edges of the shelves c , to permit the books to be removed therefrom, or to position the bars g between the shelves c , to lock the books upon the shelves and safely within the case. For thus moving the frame B, I connect to its vertical bars f , at their tops, the cords, wires, or chains h , which pass over or around the guide-pulleys i , mounted in suitable brackets, j , at the top of the case, the cords being 55 adjusted to the pulleys in any suitable manner, so that they may be led to and connected at one side of the case with a pull-cord, k , which may be drawn upon to raise the vertical bars f , and maintain the level of the cross-bars g , so that they may register evenly with the shelves c for their entire length, to look well and not interfere with the free passage of the books to and from the shelves. A ring or hook device, l , on the cord k may be engaged 60 with a pin or hook, m , on the side or back of the case for holding frame B with the bars g upon the edges of the shelves c . Suitable sockets, $e'd'$, are provided at or in the head and base of the case A, respectively, to guide and 65 stay the vertical bars f and conceal their ends. I propose to make the locking-frame bars f,g 70 of small or light-appearing and ornamental wood moldings, and to increase their strength by re-enforcing them at their backs by the metal strips or plates n .

To prevent any springing of the vertical bars f away from the sides a of the case, I 75 may slot these bars through from the front, to work on pins passed through elongated slots 80 of the bars and fixed to the sides a , said pins having heads overlapping the bars f at one or both sides of the slots; but I prefer to employ for this purpose the slotted metal plates o , fastened to the front edges of sides a , over 85 apertures p in the sides, which will permit the headed pins r , fixed in the locking-frame bars f , to work freely in and behind the plates o , the heads of pins r being passed back of plates o through enlargements s of the slots t of the 90 plates. The number of these plates o will 95 vary with the height of the case, two on each vertical side or partition of the case being generally sufficient. By the use of these plates o and pins r , the outward springing of the lock- 100

ing frame B is prevented and the appearance of the frame or case is not marred by slots or pins showing at the front.

For a simple, strong, and concealed latch device to secure the frame B with the bars *g* in position to lock the books in the case, as in Figs. 1 and 2, I employ the spring bar or plate *u*, which I fix at one end by a pin, *v*, to hold the bar *u* in a cavity, *w*, of a side *a* of the case. The bar *u* has fixed to it the rod *a'*, which passes within and along a groove, *b'*, in the front of one of the shelves *c* to the opposite side *a*. Pins or stops *c'*, fixed to bars *f* at each side, are placed to engage the rod *a'* at both ends or the said rod *a'* at one end and the head of the spring-bar *u* at the other end, as shown. The curved head *u'* of the bar *u* yields when struck by a pin *c'*, to allow the pin to pass and then springs over the pin at that side of the case, and as the lateral movement of bar *u* also moves the rod *a'* lengthwise, the other end of rod *a'* will pass below the stop *c'* of the other bar *f*, of frame B, and thus secure the frame at both sides of the case and in locked position, and to again permit the bars *g* to be raised to release the books the spring-bar *u* is to be forced back by any suitable push bit or key for throwing its head *u'* and the other end of rod *a'* clear of the pins *c'* of the frame. A slat or bar, fixed to the front of the shelf *c* over rod *a'*, conceals the rod and gives a like finish to the fronts of all the shelves. The bars *g* of the frame B are here arranged to drop to the locking position between the shelves by gravity; but the frame B may be adjusted to the case A so that the bars *g* drop to release the books, and must be raised to lock the books in the case by the cords and pulleys *h i k*, or equivalent devices, and then latched or bolted in position, the principles of action being the same in either arrangement of the frame. One or more of the bars *g* may be omitted, so that free access may always be had to the books on any one or more of the shelves *c*, as may be most desirable or conven-

ient. The bars *f g* of the locking-frame B will be firmly secured together by screws, and in practice I shall employ screw-bolts with jam-nuts in place of the headed pins *r*. When a number of books are removed from any one shelf, blocks of wood or tin to fill the spaces may be employed to hold the line of books upright and prevent removal of volumes on their side.

I do not abandon or dedicate to the public any patentable feature set forth herein and not hereinafter claimed, but reserve the right to claim the same either in a reissue of any patent that may be granted upon this application or in other applications for Letters Patent that I may make.

Having thus described my invention, I claim as new and desire to secure by Letters Patent—

1. The combination, with a book-case having shelves *c*, of the vertically-movable frame B, provided with horizontal cross-bars *g*, as and for the purposes specified.

2. The combination, with the book-case A and the movable frame B, formed of vertical and horizontal bars *f g*, of the adjusting cords and pulleys *h i k*, substantially as shown and described.

3. The combination, with the book-case A and the movable locking-frame B, of the slotted plates *o*, fixed to the case, and the headed pins *r*, fixed to the vertical bars *f* of the movable frame, substantially as shown and described.

4. The combination, with the book-case A and the movable locking-frame B, carrying the pins *c'*, of the spring latch-bar *u a'*, substantially as shown and described.

5. The combination, with the book-case A, of a movable locking-frame, B, consisting of vertical and horizontal bars *f g*, re-enforced at the back by the metal plates *n*, substantially as shown and described.

WM. A. SMITH.
